[57] CLAIM

The ornamental design for an integrated lumbar support and air pump unit for a vehicle seat, as shown and described.

DESCRIPTION

FIG. 1 is a perspective view of an integrated lumbar support and air pump unit for a vehicle seat, showing my new design; the broken lines are for environmental purposes only and form no part of the claimed design;
FIG. 2 is a front elevational view thereof;
FIG. 3 is a top plan view thereof;
FIG. 4 is a rear elevational view thereof;
FIG. 5 is a bottom plan view thereof;
FIG. 6 is a left side elevational view thereof; and,
FIG. 7 is a right side elevational view thereof.
